COMBINATION BED LAMP AND RADIO RECEIVER

William H. Silvers, Pittsburgh, Pa.

Application May 4, 1948, Serial No. 146,163

Term of patent 14 years

(Cl. D56—4)

To all whom it may concern:

Be it known that I, William H. Silvers, a citizen of the United States, residing in Pittsburgh, in the county of Allegheny and State of Pennsylvania, have invented a new, original, and ornamental Design for Combination Bed Lamp and Radio Receiver, of which the following is a specification, reference being had to the accompanying drawing, forming part thereof.

In the drawing:

Fig. 1 is a perspective view of a combination bed lamp and radio receiver, showing my new design;
Fig. 2 is an end elevation of the same; and
Fig. 3 is a top plan view of the same.

I claim:

The ornamental design for a combination bed lamp and radio receiver, as shown.

WILLIAM H. SILVERS.
